UNITED STATES PATENT OFFICE

LELDON H. TAPSCOTT, OF TUSCALOOSA, ALABAMA

DESIGN FOR A GRAVE MARKER

Application filed October 28, 1931. Serial No. 41,551. Term of patent 14 years.

To all whom it may concern:

Be it known that I, LELDON H. TAPSCOTT, a citizen of the United States of America, residing at Tuscaloosa, in the county of Tuscaloosa and State of Alabama, have invented a new, original, and ornamental Design for a Grave Marker, of which the following is a specification, reference being had to the accompanying drawings, forming a part hereof.

Figure 1 is a perspective view.

Figure 2 is a similar view looking toward the rear face of the design.

Figure 3 is a top plan view.

Figure 4 is a transverse sectional view on the line 4—4 of Figure 1, looking in the direction of the arrows.

I claim:

The ornamental design for a grave marker, as shown.

LELDON H. TAPSCOTT.
